UNITED STATES PATENT OFFICE

168,024

VISOR FOR SPECTACLES OR SIMILAR ARTICLES

Robert P. Evans, Westwood, Mass., assignor to Visual Research Incorporated, Boston, Mass., a corporation

Application January 23, 1952, Serial No. 18,184

Term of patent 14 years

(Cl. D57—1)

To all whom it may concern:

Be it known that I, Robert P. Evans, a citizen of the United States, residing at Westwood, in the county of Norfolk, in the Commonwealth of Massachusetts, have invented a new, original, and ornamental Design for a Visor for Spectacles or Similar Articles, of which the following is a specification, reference being had to the accompanying drawing, forming a part thereof, in which:

Fig. 1 is a top plan view of a visor for spectacles or similar articles showing my new design.
Fig. 2 is a front elevational view thereof;
Fig. 3 is a rear elevational view;
Fig. 4 is a side elevational view; and
Fig. 5 is a front perspective view.

I claim:

The ornamental design for a visor for spectacles or similar articles, substantially as shown.
ROBERT P. EVANS.
